UNITED STATES PATENT OFFICE.

PHILIP A. MYERS, OF ASHLAND, OHIO, ASSIGNOR TO F. E. MYERS & BROTHER, OF SAME PLACE.

DESIGN FOR A PUMP-FRAME.

SPECIFICATION forming part of Design No. 30,103, dated January 31, 1899.

Application filed January 5, 1899. Serial No. 701,269. Term of patent 14 years.

To all whom it may concern:

Be it known that I, PHILIP A. MYERS, of Ashland, Ohio, have invented and produced a new Design for Pump-Frames, of which the following is a specification.

In the accompanying drawings, Figure 1 is a side elevation of the pump-frame. Fig. 2 is a plan view. Fig. 3 is a view of one end, and Fig 4 a view of the opposite end.

10 The leading features of my design consist in the shape or general outline of the frame and also in its surface configuration.

As shown in the drawings, the body or cylinder is shown at A, having a central cylindrical surface *a*, bordered by an upper plain surface *b*. The base *b'* flares downwardly and outwardly, as shown in Figs. 1, 3, and 4, and has a series of elongated openings through

it. Centrally of the frame rises a cylinder *B*, having a contracted neck portion *c*. On each side of the center, at the ends of the part *b*, are caps *d d*. A yoke *e* projects from one end of the cylinder, and the opposite end supports a plate *g*, carrying on each end of the upper part thereof curved plates *f*. The plate *g* also carries a bearing *h* near its center and a second bearing *i* at its upper end.

What I claim is—

20 The design for a pump-frame as herein shown and described.

25 In testimony whereof I affix my signature in presence of two witnesses.

PHILIP A. MYERS.

30 Witnesses:

OAK McCRAY,
F. B. KELLOGG.
